EARTH SAMPLING TOOL

Claude C. Laval, Jr., Fresno, Calif.

Application September 13, 1954, Serial No. 455,620

15 Claims. (Cl. 255—1.4)

The present invention relates to geological apparatus of the earth sampling character and more particularly to improvements in coring tool construction and operation.

It is a conventional practice to obtain samplings of soil and rock formations prior to, or during, the performance of certain subterranean operations such as drilling wells for oil, water, gas, minerals or the like, during tunneling and mining operations; and in preparation for dam and building construction where dependable foundations are necessary. The well-known apparatus for obtaining such samplings generally consists of a cylindrical or similarly formed tool having a sample-receiving barrel therein. Such tools are lowered into a bore hole or exploratory cavity in the earth's surface and by hydraulic, explosive, geared or some other pressure applying means, the tools are driven into earth penetrating engagement. An apparatus of this nature is shown in a copending U. S. patent application S. N. 455,619, filed September 13, 1954. Therein are discussed several problems encountered in this field and the subject matter of that invention deals with improvements in the complete sampling apparatus.

This application pertains to the sampling tools themselves and the improvements hereinafter more fully described are adaptable to various types of sampling apparatus irrespective of the driving means and other details of associated structure employed. As noted in my copending application cited above, conventional sampling tools have frequently been known to stick, jam, lock or otherwise anchor in penetrated engagement in an earth formation. With sampling operations conducted at considerable depths, this represents a serious problem, resulting in damage of the sampling apparatus, breakage of sampling tools, jamming of the bore hole and sometimes complete loss of the apparatus and consequent plugging of the hole.

Another problem of considerable consequence is sample loss during withdrawal of the tool from the hole. In order to counteract sample loss from the tools subsequent to collection thereof and particularly in those tools withdrawn from the bore hole in dangling fashion, the interior of the conventional core-receiving barrel has been contoured in such a way as to permit easy entry of the sample into the barrel but to restrict its exit. Such a feature is shown in the U. S. patent to Miller, Patent No. 2,334,428. This device employs serrations at the mouth of the barrel. This structure has met with success insofar as preventing sampling loss is concerned but has introduced an additional problem. When it is desired to remove the sample collected for inspection and analysis, the serrations function equally as well to prevent convenient dislodgement of the sample from the barrel. With samplings packed hard within the barrel and with rock samples, considerable prying, digging and scraping is necessary to extract the sample. Oftentimes a sample becomes jammed in the barrel and fracture of the tool is necessary to remove it. In other instances, the sample must be granulated for removal, thus reducing the intelligence to be gained by its inspection. This construction completely

2

prevents removal of the sample in the exact shape it assumes in the barrel, a procedure sometimes found desirable.

Accordingly, an object of this invention is to facilitate removal of sampling tools from earth penetrating engagement thus minimizing or preventing sticking, jamming and inadvertent anchoring of such tools.

Another object is to provide an expendable covering member between a sampling tool and earth penetrated thereby adapted to remain in the earth during removal of the tool.

Another object is to reduce friction between a sampling tool and earth penetrated thereby.

Another object is to minimize the development of a partial vacuum and the consequent suction between an earth penetrating member and the surrounding earth formation.

Another object is to provide an expendable sleeve slidably fitted over a sampling tool adapted to remain in an earth formation when the tool is removed.

Another object is to minimize the development of suction between the sleeve as provided in the foregoing paragraph and the sampling tool during extraction thereof from earth penetrating engagement.

Another object is to provide a device as set forth in the preceding paragraphs which in no way impedes the sample collecting action of the sampling tool.

Another object is to facilitate removal of a sample from a sampling tool which is designed to prevent sample loss during removal thereof from a bore hole.

Another object is to provide a sampling tool having an irregularly contoured core-receiving barrel adapted to minimize sample loss with convenient means for extraction of the sample from the barrel.

Another object is to obviate the need for digging, prying and scraping of collected samples from earth sampling tools.

Another object is to provide a sampling tool adapted to permit removal of a sample in substantially the exact shape and form collected.

Another object is to provide a sampling tool which is separable into a plurality of parts to permit easy removal of samples therefrom.

Other objects are to provide a sampling tool in accordance with the foregoing objects which is simple to manufacture, durable in construction, readily adaptable to many types of sampling apparatus and which provides features highly effective for the intended purposes.

These and other objects will become more fully apparent upon reference to the following description.

In the drawings:

Fig. 1 is a longitudinal cross section taken through a bore hole and showing the sampling tool of the present invention and suitable operating mechanism therefor inserted therein.

Fig. 2 is a fragmentary longitudinal cross section similar to Fig. 1 but showing a different operating mechanism for the sampling tool.

Fig. 3 is a somewhat enlarged transverse cross section taken through the sampling apparatus shown in Fig. 1.

Fig. 4 is a view similar to Fig. 3 but showing the sampling tool in its extending limit of operation.

Fig. 5 is a somewhat enlarged longitudinal cross section taken through the sampling tool of Figs. 3 and 4.

Fig. 6 is an exploded perspective view of the sampling tool as provided by the present invention.

Referring more particularly to the drawings:

A sampling apparatus 10 is shown in Fig. 1 being held by a cable 11 within a bore hole 12 containing fluid 13. This sampling apparatus provides a mounting structure for a plurality of sampling tools 14 housed therein.

The sampling apparatus provides a substantially cylind-

drical housing 20 elongated in form and having a mounting body or block 21 rigidly secured therein. The mounting body 21 provides a plurality of transversely disposed longitudinally spaced ramming chambers 22 adapted to receive the sampling tools 14 for slidable reciprocation between a retracted position within the chamber and a position extended from the housing, the latter position being that shown in Fig. 1.

Each of the ramming chambers 22 provides a closed end 30 and an open end 31 opening exteriorly of the housing 20. An annular nut 32 is threadably received in the open end of the chamber and provides a central bore 33 extending therethrough axially aligned with the chamber.

The sampling tool 14, as provided by the present invention, is best shown in Fig. 6. Its construction includes a pair of semi-cylindrical keyed segments 40 each having threaded ends, as 41. The segments are arranged in interfitted elongated tubular relation thereby defining an outer wall 42 and an interior core-receiving barrel 43. An annular nut 44 is threadably fitted on one of the threaded ends 41 of the interfitted segments herein-after referred to as the penetrating or cutting end thereby maintaining them in interfitted relation. The outer wall 42 is inwardly directed at the penetrating end and is provided with a plurality of grooves or bores 45 constituting breather openings extending longitudinally therethrough.

The core-receiving barrel 43 is provided with a plurality of longitudinally spaced annular serrations, threads or ribs, indicated at 46. It will be noted that these serrations are convergently inclined from the penetrating end of the barrel toward the other end, conveniently referred to as the mounting end. The core-receiving barrel is adapted to receive therein a sample of an earth formation, such soil or rock, being slidably received over the serrations during its inward travel within the barrel. The sample is retained within the barrel because of the radially inwardly directed ridges on the serrations which prevent or restrict outward movement of soil or rock once having been received within the barrel.

A ram 50 is provided in the chamber 22 for slidable reciprocation between a retracted position adjacent to the closed end 30 of the chamber and an extended position adjacent to the open end 31 of the chamber. The ram includes a piston head 51 and an extended body portion 52 disposed toward the open end of the chamber. The body portion is provided at its end with a countersunk threaded bore 53. At the inner end of this bore 53, an annular passage 54 is provided. The body portion also has a longitudinal passage 55 permitting communication between the annular passage and the ramming chamber through the body portion. The body portion further provides an inclined passage 56 establishing communication between that portion of the chamber 22 behind the piston head and a position centrally disposed of the annular passage 54 and within the threaded bore 53. A ball check valve member 57 having a threaded plug 58 is fitted in the inclined passage 56 permitting the passage of gases and fluids only in a direction toward the ramming chamber adjacent the rear face of the piston head. The plug 58 is provided with a longitudinal bore permitting gaseous passage therethrough. The piston head is also provided with an ellipsoidal depression 59 concentrically arranged therein which also extends somewhat into the body portion 52.

The ram 50 is fitted onto the sampling tool 14 by threadably connecting the bore 53 on the mounting end of the interfitted cylindrical segments 40. In this position the longitudinal grooves 45 are aligned with the annular passage 54 in the body portion 52. Furthermore, the wall 70 thickness of the cylindrical segments overlaps the annular passage 54 isolating the core-receiving barrel 43 of the tool from such annular passage. Thus, it becomes evident that the inclined passage 56 and valve 57 permit uni-directional gaseous passage from the core-receiving barrel to 75

the ramming chamber 22 rearwardly of the piston head 51.

With the ram 50 and separably constructed sampling tool 14 threadably connected, a sleeve or cap 65 providing a cylindrical portion 66 and an annular inwardly directed flanged end 67 is slidably fitted over the outer wall 42 of the cylindrical segments 40. The flanged end bears against the outer end of the cylindrical segments and closes off the longitudinal grooves 45 therein. It is to be understood that segments 40 can be held in fitted relation by the sleeve alone, that is, by forming the penetrating end without threads and eliminating the annular nut 44. In this event, the mounting end is still threadably connected to the ram so as to maintain the segments together when the sleeve is removed.

Thus, the ram 50, sampling tool 14 and sleeve 65 are adapted for unitary movement between a retracted position within the chamber, as shown in Fig. 3, and an extended position exteriorly of the housing 20, as shown in Fig. 4. A spring 75 is provided in the chamber encompassing the ram and sampling tool and bearing at opposite ends against the annular nut 32 and the piston head 51, respectively.

In its retracted position, the piston head 51 is spaced somewhat from the closed end 30 of the chamber 22. An explosive charge of powder or the like, indicated at 80, preferably a shaped charge, is placed within this space, also filling the ellipsoidal depression 59 in the piston head 51 and body 52. A frusto-conical nose 81 extends in an embedded position within the explosive charge and provides thereon a threaded fitting 82 for threadable insertion into an opening 83 in the wall of the housing 20. A spark gap firing pin or igniting mechanism 84 is also embedded within the explosive charge and a control wire 85 is connected to the firing pin for extension upwardly in mounting block 21. Suitable packing seals, not shown, may be provided to render fitting 82 fluid-tight, if found desirable.

A control mechanism 90 is mounted in the upper end 40 of the housing 20 and functions to permit selective actuation individually or collectively of the several sampling tools 14 provided in the housing 20 according to predetermined adjustment. Each of the wires 85 lead into the control mechanism and a single control wire 91 extends therefrom upwardly through the housing. This arrangement forms no part of this particular invention and is described in greater detail in my copending application S. N. 455,619, filed on September 13, 1954.

50

Operation

The operation of this invention is believed to be readily apparent and is briefly summarized at this point. Initially, all of the sampling tools 14 provided in the housing 20 are urged into their retracted positions by their respective springs 75. The space behind the piston heads 51 are filled with explosive powder or charge 80 and the noses 82 by means of the threaded fittings 83 are screwed tightly in place in the housing wall 20. Thus, conditioned for operation, the sampling apparatus 10 is lowered into a bore hole or other cavity in the earth wherein it is desired to extract a sampling of the earth formation.

When the device is positioned at the desired level a 65 switch, not shown, at the surface of the wall or some other convenient remote controlling station, is closed whereupon the control mechanism 90 is effective to ignite one of the firing mechanisms 84 associated with its respective sampling tool 14.

The explosion created behind the piston head 51 thrusts the ram together with the sampling tool 14 outwardly from a position such as that shown in Fig. 3 into its extended position, as shown in Fig. 4. During this outward travel, it will be noted that the ball check valve member 57 maintains the inclined passage 56 closed

whereby the explosive gas pressures are confined within the ramming chamber 22 for desired driving effect.

The force created by the explosion is sufficiently great to extend the sampling tool 14 into deeply penetrated position within even very hard earth formations. As the sampling tool enters the formation, a sampling of the formation is received within the barrel 43 and passes easily over the serrations 46 provided on the interior wall thereof. However, such formation or sampling is retained within the barrel because the edges of the serration prevent or restrict the outward movement of the sample, once it enters the barrel. When the sampling tool has reached its substantially fully extended position, and the sample being packed in the barrel 43 reaches substantially the inner end of the barrel, it is possible that air or other fluid may be trapped between the inner end of the sample entering the barrel and the inner end of the barrel itself. For this reason, the inclined passage 56 has been provided. It will be quite evident that a sample entering the barrel will force fluid or gases captured therein outwardly through the inclined passage and past the ball check valve member 57. Since this action only occurs at substantially the fully extended position of the sampling tool, and because of the relatively high pressure of the explosion during the expansion stroke of the sampling tool, there is little danger that the ball check valve member will open to release any of the explosive force built up behind the piston head. It will be understood that an equalizing of pressures between the barrel 43 and that portion of the ramming chamber 22 behind the piston head has little effect on the operation of the sampling tool if this equalization occurs at substantially the fully extended position of the tool.

When the tool has reached its fully extended position and is ready for retraction due to dissipation of the explosive charge and the urging of spring 75, its emergence from the formation is rendered easier by the provision of sleeve 65. It will be apparent that the sleeve 65 has been driven into the formation along with the cylindrical segments 40. On the retraction stroke of the ram the sleeve remains in the formation and the sampling tool is slidably withdrawn therefrom. Thus, the sleeve acts as a liner between the earth formation and the outer wall 42 to reduce friction between the formation and the tool. However, in order to prevent a partial vacuum from developing between the sleeve 65 and the cylindrical segments 40, the groove 45, the annular passage 54, and the longitudinal passage 55 have been provided. Thus, there is an equalization of pressure between the ramming chamber 22 and the area between the sleeve 65 and the end of the cylindrical segments 40. This prevents sticking between the sleeve and the cylindrical segments and greatly facilitates separation of these members during the retraction stroke.

After the sampling apparatus 10 has obtained a plurality of earth samples at a single testing position or at a variety of depths, as the case may be, it is withdrawn from the bore hole. At the surface of the hole, the fittings 83 are removed and the tool forced out of the housing a distance permitting the cylindrical segments 40 to be grasped and unthreaded from the ram. The segments, still containing a collected sample, are then ready to be taken to a laboratory or the like for removal and analysis of the sample or simple observation thereof. For this purpose, the segments are separated from one another by removing the annular nut 44 therefrom. This separable construction of the sampling tool permits easy access to the sample which has been received in the barrel 43. It has been found that when the annular serrations 46 are used to prevent the loss of samples after having once entered the barrel, it becomes quite difficult to remove, scrape or otherwise obtain the sample therefrom. Further, it is sometimes desirable to keep a sample intact in the shape cored from the formation. With the sam-

pling tool constructed of separable segments, these problems are obviated quite easily.

After the samples have been removed, the segments are again positioned in interfitting relation and replaced in mounting position within the ramming chambers. A new charge of explosive powder is placed in the chamber and the apparatus is generally reset for subsequent utilization.

Although the above description provides a sampling tool for use in a sampling apparatus, such as shown at 10 in Fig. 1, the construction of the sampling tool may be employed in a sampling apparatus 100, such as shown in Fig. 2. That is, the construction of the sampling tool including sleeve 65 is not to be limited to any particular means for driving the tool into earth penetrating engagement. The apparatus is the one shown in greater detail in my copending application S. N. 454,543, filed on September 7, 1954. Briefly, it includes a housing 101 mounted in a bore hole 102 and has a mounting body or block 103 disposed for slidable reciprocation in the housing. A plurality of sampling tools 104 are mounted on the body 103 and are adapted for outward pivoting movement through slots 105 in the housing, in upward arcs through the walls of the bore hole and into grooves 106 disposed within the mounting body 103. The sampling tools 104 are constructed in the same manner as the tools 14, providing separable segments, serrations on the core-receiving barrel and a sleeve, as 107, in Fig. 2, slidably received on the connected cylindrical segments. Pins 108 pivotally mounted in the block have mounting portions 109 thereon which provide threaded female bores for connection to the interfitting segments in the same manner as ram 50 is connected to the segments, as seen in Fig. 6. The operation of these tools is similar to that discussed in relation to Fig. 1 in that as the tools move in upward arcs through the soil formation the sleeves 107 are left in embedded position within the formation thus permitting easy withdrawal of the tools from the formation for movement into the grooves 106.

Although a cylindrical tool and cylindrical sleeve have been shown and described hereinabove, it will be apparent that other shapes such as rectangular, oval, triangular and the like may be used.

Other features which could be incorporated in the various means for embedding and retracting the tools of the present invention have not been shown in the drawing for drafting simplicity and to emphasize the more significant features of the present invention. However, as in my copending application, S. N. 455,619, filed on September 13, 1954, venting passages and cooperating latch means may be provided in the embedding and retracting apparatus, especially with that of Figs. 1 to 5 employing explosive drive means for the tool. Likewise, a separable sampling tool and an expendable sleeve can be provided in a telescoping sampling tool, such as that shown in my copending application S. N. 455,619, filed September 13, 1954.

It will be apparent from the foregoing description that the present invention provides features in a sampling tool apparatus which ensure withdrawal of the tool from the sampled formation and greatly facilitate removal of the sample from the tool. Both problems have limited the effective use of well-known sampling apparatus. The present invention provides a simple, economical and readily adaptable means for solving these problems.

Although the invention has been herein shown and described in what is conceived to be the most practical and preferred embodiment, it is recognized that departures may be made therefrom within the scope of the invention, which is not to be limited to the details disclosed herein but is to be accorded the full scope of the claims so as to embrace any and all equivalent devices and apparatus.

Having described my invention, what I claim as new and desire to secure by Letters Patent is:

1. A coring tool comprising an elongated tubular member having a mounting end portion and an opposite cutting

end portion, the tubular member having a wall defining a core-receiving bore and having a breather opening longitudinally through the wall, and a sleeve slidably fitted over the cutting end portion of the tubular member having an annular inturned edge endwardly overlying the cutting end portion of the tubular member and the open end of the breather opening therein.

2. A coring tool comprising an elongated tubular member having a mounting end portion and an opposite penetrating end portion, said member being divided longitudinally into separable elements, said tubular member having a breather opening longitudinally through an element thereof from the mounting end portion to the penetrating end portion, and a sleeve slidably fitted over the tubular member in circumscribing relation to the elements having an annular inturned flange outwardly overlying the penetrating end portion of the tubular member and the end of the breather opening therein.

3. A coring tool comprising an elongated tubular member having a mounting end portion and an opposite penetrating end portion, said member being divided longitudinally into separable elements, said tubular member having a breather opening longitudinally through an element thereof from the mounting end portion to the penetrating end portion; annular means screw-threadably mounted in circumscribing relation on opposite ends of the tubular member constraining the elements thereof to their tubular arrangement; and a sleeve slidably fitted over the penetrating end portion of the tubular member in circumscribing relation to the annular means at said end and the elements of the member and having an annular inturned flange endwardly overlying the penetrating end portion of the tubular member and the end of the breather opening therein.

4. In a geological apparatus for use in sampling earth formations, a sampling tool comprising a substantially cylindrical member having an outer wall and an interior core-receiving barrel open at both ends, a plurality of bores extending through the wall of the cylindrical member open at both ends thereof, a mounting head releasably fitted on the cylindrical member in closing relation to one end of the barrel and having a passage providing communication between the bores in the cylindrical member and the exterior of the head, a sleeve providing a substantially cylindrical portion slidably fitted over the outer wall of the cylindrical member and having an inwardly flanged end fitted in closing relation to the bores at the opposite end of the barrel from the head, and means for urging the tool into penetrating engagement with an earth formation and for removing the tool from such formation.

5. A geological apparatus for use in sampling earth formations comprising a sampling tool having a pair of semi-cylindrical segments arranged in interfitted relation forming an exterior wall and an interior core-receiving barrel open at both ends, means releasably retaining the segments in barrel forming relation, a mounting head releasably fitted in closing relation on one end of the barrel, a sleeve slidably fitted over the outer surface of the semi-cylindrical segments having an open end aligned with the other open end of the barrel, the barrel having a plurality of annular inwardly inclined serrations therein permitting inward movement but restricting outward movement of a sample relative to the barrel, the mounting head having a passage providing communication between the exterior of the head and the barrel, and means for extending the sampling tool into earth penetrating engagement and for retracting the tool from such engagement.

6. A geological apparatus for use in sampling earth formations comprising a sampling tool having a pair of semi-cylindrical segments arranged in interfitted relation forming an exterior wall and an interior core-receiving barrel open at both ends, the wall having a plurality of bores longitudinally extending therethrough, means re-

leasably retaining the segments in barrel forming relation, a mounting head releasably fitted in closing relation on one end of the barrel and having an annular passage communicating with said bores, a sleeve slidably fitted over the outer surface of the semi-cylindrical segments having an open end aligned with the other open end of the barrel, the barrel having a plurality of annular inwardly inclined serrations therein permitting inward movement but restricting outward movement of a sample relative to the barrel, the mounting head having a first passage providing communication between the exterior of the head and the barrel and a second passage providing communication between the annular passage and the exterior of the head, and means for extending the sampling tool into earth penetrating engagement and for retracting a tool from such engagement.

7. A geological sampling apparatus comprising a body member providing a chamber therein, a sampling tool mounted in the chamber for reciprocation between a retracted position within the chamber and a position extended from the body adapted in the extended position to receive an earth sample, the sampling tool having a plurality of releasably connected interfitted fracto-cylindrical segments forming interiorly thereof a core-receiving barrel, the barrel having annular serrations therein permitting movement of the sample inwardly of the barrel but restricting outward movement of such a sample, a sleeve slidably received over the interfitted segments adapted to remain in embedded position within an earth formation during movement of the cylindrical segments from extended to retracted position, means yieldably urging the tool into retracted position, explosive means for thrusting the tool into extended position, and control means for firing the explosive means.

8. A sampling apparatus for insertion into earth cavities comprising a housing having a slot therein, a mounting member mounted for slideable movement within the housing past the slot and having a groove therein disposed for alignment with the slot, a sampling tool connected to the mounting member adapted upon registration with the slot for pivotal movement in an upward arc through the earth formation adjacent thereto from a dependent position relative to the mounting member to an upright position within the groove of the mounting member, the sampling tool including a plurality of releasably connected interfitted fracto-cylindrical segments having an outer wall and an interior core-receiving barrel, the barrel having a plurality of annular inwardly inclined serrations adapted to permit entry but restrict exit of a sample relative thereto, a sleeve slidably fitted over the outer wall of the segments adapted to remain embedded in an earth formation thereby facilitating slideable withdrawal of the tool, and means for moving the mounting member toward the slot for registration of the tool therewith and for moving the mounting member past the slot to enable entry of the tool into the earth formation and for further movement into its upright position within the groove of the mounting member.

9. A coring tool comprising an elongated tubular member having an open mounting end portion and an open opposite penetrating end portion, the tubular member having a wall defining a core-receiving bore and having a breather opening extended longitudinally through the wall; a mounting head connected to the mounting end portion in closing relation thereto having passages providing communication between the exterior of the head and the breather opening; and a sleeve slidably fitted over the cutting end portion of the tubular member having an annular inturned edge endwardly overlying the penetrating end portion of the tubular member and the open end of the breather opening therein.

10. A coring tool comprising an elongated tubular member having a mounting end portion, an opposite penetrating end portion, a wall defining a core receiving barrel, and a breather opening extended longitudinally

through the wall from the mounting end portion to the penetrating end portion; a mounting head releasably fitted on the penetrating end portion of the tubular member having a passage extended from the barrel to the exterior of the head and a passage extended from the breather opening to the exterior of the head; and a sleeve slidably fitted over the tubular member in circumscribing relation to the tubular member having an annular inturned flange endwardly overlying the penetrating end portion of the tubular member and the end of the breather opening therein.

11. In a geological apparatus for use in sampling earth formations, a sampling tool comprising a tubular member having an outer wall and an interior core-receiving barrel open at opposite ends, a bore extended through the wall of the tubular member open at opposite ends of said member, a mounting head connected to the tubular member in closing relation to one end of the barrel and having a passage providing communication between the bore in the cylindrical member and the exterior of the head, a sleeve slidably fitted over the outer wall of the tubular member and having an inwardly flanged end fitted in closing relation to the bore at the opposite end of the barrel from the head, and means for urging the tool and sleeve into penetrating engagement with an earth formation and for removing the tool from such formation, the sleeve being slidably removable from the tool to remain in the formation.

12. A geological sampling apparatus comprising a body member providing a chamber therein, a sampling tool mounted in the chamber for reciprocation between a retracted position within the chamber and a position extended from the body adapted in the extended position to receive an earth sample, the sampling tool having a plurality of releasably connected segments forming interiorly thereof a core-receiving barrel, a sleeve slidably received over the interfitted segments adapted to remain in embedded position within an earth formation during movement of the cylindrical segments from extended to retracted position means yieldably urging the tool into retracted position, and explosive means for thrusting the tool into extended position.

13. A sampling apparatus for insertion into earth cavities comprising a housing having a slot therein, a mounting member mounted for slidable movement within the housing past the slot and having a groove therein disposed for alignment with the slot, a sampling tool connected to the mounting member adapted upon registration with the slot for pivotal movement in an upward arc through the

5 earth formation adjacent thereto from a dependent position relative to the mounting member to an upright position within the groove of the mounting member, a sleeve slidably fitted over the tool adapted to remain embedded in an earth formation upon withdrawal of the tool therefrom thereby facilitating slidable withdrawal of the tool, and means for moving the mounting member toward the slot for registration of the tool therewith and for moving the mounting member past the slot to enable entry of the tool into the earth formation and for further movement into its upright position within the groove of the mounting member.

14. A coring tool comprising an elongated tubular member having a mounting end portion and an opposite cutting end portion, said tubular member having a core receiving bore extended longitudinally thereof from the cutting end portion, and a sleeve member slidably fitted over the cutting end portion of the tubular member, one of said members providing a breather passage having 15 a breather opening at the cutting end portion of the tubular member and overlaid by said sleeve member during cutting operations to exclude foreign material from said breather passage.

15. A coring tool comprising an elongated tubular member adapted for longitudinal reciprocation during coring operations having a mounting end portion and an opposite cutting end portion, said tubular member having a core receiving bore extended longitudinally thereof from the cutting end portion, and a sleeve member slidably 20 fitted over the cutting end portion of the tubular member having an annular inturned edge endwardly overlying the cutting end portion of the tubular member, one of said members providing a breather passage longitudinally therethrough in spaced relation to the core receiving bore and shielded from the core receiving bore by the 25 tubular member, said passage having a breather opening overlaid by the inturned edge of the sleeve member.
